WALL COVERING

John Tomec, Trenton, N. J.

Application June 1, 1935, Serial No. 24,472

4 Claims. (Cl. 41—34)

My invention relates to wall coverings and particularly to wall coverings of a durable and washable character having a highly decorative and novel appearance.

5 The walls of a room are usually provided with a wooden baseboard and with wall paper or tinted surfaces extending from the baseboard to the ceiling or to a picture moulding. The wall paper and tinted surfaces soon become dirty or marred, especially when children are about, and therefore the paper has to be replaced frequently or the walls retinted. This continual renewal or redecoration of rooms and walls is expensive and inconvenient, particularly in premises that are 10 rented and which must be renovated for each new tenant.

These disadvantages are partially overcome when the room is provided with wainscoting or wood panelling but such constructions are expensive to install and are not usually desirable for use in bedrooms, nurseries and in many other places.

In accordance with my invention difficulties and disadvantages of the prior art are overcome 25 by the use of material of a durable character resistant to wear and abrasion and presenting a decorative surface which preferably is capable of being washed or cleaned to restore its attractive appearance. The product may be made with 30 a portion to simulate a baseboard together with one or more portions simulating wood panelling, wainscoting or wall paper in any combination or design desired. My invention is particularly adapted for use in renovating, inexpensive 35 house developments and repair work where a saving in time, labor and expense is of importance. The elements of the wall covering may be formed separately but I prefer to include portions representing two or more of such elements 40 in a single piece.

In the preferred embodiment of my invention the material is made in the form of a strip or panel which may extend from the ceiling to the floor or to the baseboard of a room if such is 45 used. However, the strips may only extend to a picture moulding or to the edge of existing wainscoting, tile or other wall construction. The strips may conveniently be made with a suitable base of water-proof or impregnated material such as 50 water-proof, or treated paper or light and flexible asphalt saturated felt although the invention is also capable of application to other flexible materials or to rigid materials such as fiber boards, pulp board, plaster board, cement-asbestos product, plywood or the like. I may thus

provide either a very light and flexible inexpensive product or a rigid one having a veneer which may be formed of relatively expensive material or constructed to possess heat or sound insulating properties.

The surface of the material which is exposed when the strips are in place and to which novel decorative effects may be given may be formed in any suitable manner and preferably is provided with a coating of water resistant and durable material such as enamel or lacquer adapted to be applied in a printing operation. The strips are preferably provided with borders on the ends thereof which are to be located adjacent the floor and ceiling of the room, these borders being different in appearance, formation, or character from that portion of the strip between the same. For example, the border on that end of the strip which is to be located adjacent the floor may be treated to simulate a section of a baseboard while the 20 border located on the opposite end of the strip may serve as a ceiling border. While either or both borders may be formed by the use of a portion which is thicker or thinner than the remainder of the strip or otherwise formed to 25 give the desired effect, I prefer to form the borders simply by printing or otherwise applying water resistant material to that portion of the strip adjacent the ends thereof, in order to give the borders the desired design or appearance. 30

Strips of material formed as described may be readily applied to the walls of rooms having ceilings of different heights without detracting from the appearance of the wall covering and without sacrificing the advantages of the material. For 35 instance by forming the borders at the ends of the strips of the greatest width consistent with good design a portion of either or both borders may be trimmed off to shorten the strip and enable it to be applied to the walls of rooms 40 having relatively low ceilings. Furthermore the wall covering may be used in rooms which do not have baseboards or may be used to replace the baseboards previously employed by forming the lower border to simulate the baseboard. A 45 substantial saving in the cost of building or renovating premises may thereby be effected without sacrifice to the appearance or durability of the wall covering. If, however, a baseboard is already provided and is to be used the lower border 50 of the strip may be trimmed off without affecting the design carried by the main body of the strip or detracting from the usefulness of the material. It is also possible to remove a section 55 from the body of the material adjacent either

or both borders to adapt the wall covering for use in very low rooms, such as recreation rooms in basements or attics.

A particular feature of my invention resides 5 in the fact that the product may be produced by printing operations either on an ordinary flat bed, block printing machine or by the use of roll printing operations. When using block printing machines of the type now used for printing 10 felt base floor coverings I may take advantage of the fact that such machines are usually made nine feet or more in width to print felt base rugs measuring 9 by 12 feet or 6 by 9 feet. These machines are therefore adapted for printing 15 wall covering material embodying my invention which is in the form of strips or panels 9 or more feet in length and adapted for use on the walls of any room with a ceiling from say 7 to 9 feet high or even higher.

20 The printing blocks used on such machines are usually 18 inches in width although at times blocks of 24 or even 36 inches in width may be used. The blocks extend all the way across the machine and therefore strips embodying my invention and having substantially the same dimensions as the printing blocks may be very readily produced by simple printing operations in which the whole design, including baseboard, wainscoting, wallpaper and ceiling border portions 25 in any desired arrangement, may be printed or applied to each strip or panel while using only a single set of printing blocks. A complete design can thus be applied to each successive section of a web of material or to each of a series of successive sheets or units of either flexible or rigid material as they are passed through the machine. The web of material or the units may thereafter be severed transversely as necessary or desired to form strips which are 9 feet in 30 length and 18 inches in width or of other dimensions corresponding to those of one or more of the printing blocks used in printing the material.

If preferred each portion of the design may 45 be printed by a different set of blocks, in which case those blocks which carry the baseboard and the wainscoting portion of the design may have cut or embossed areas which are relatively small so that the cost of cutting the blocks will be 50 much less than in ordinary operations wherein the design extends over a large area of the block. Furthermore, the same baseboard and wainscoting design can be used with a great variety of 55 wall paper designs and therefore by changing only one set of comparatively inexpensive printing blocks a large section of designs can be produced.

Material embodying my invention and having 60 a rigid base may be applied directly to the studding when constructing or renovating inexpensive buildings to provide a durable wall covering having a very attractive appearance. The studdings ordinarily are erected only 16 inches apart and therefore the strips should be only 16 65 inches in width so that the edges of each strip will rest on the studding. By using printing blocks carrying a design only 16 inches in width an unprinted marginal edge one inch in width 70 will be left on each side of the printed area of each sheet or unit. These unprinted edges will be trimmed off in applying the strips so that an accurate fit can be obtained between adjacent strips and great care and accuracy in severing or forming the edges of sheets or units is not 75 required. Moreover any damage to the edges of

the strips will be of no consequence and materials which otherwise would have to be discarded can be used effectively.

When printing, embossing or otherwise forming the material by means of a roller the web, 5 lengths or units of the material may be passed through the rolls so as to be printed or formed either lengthwise of a narrow web or transversely of a wide web from which they may be severed or separated. Since the material used need only 10 be comparatively narrow I may use scrap products or waste material from rug making, sheet forming or fiber-board manufacturing operations.

In applying material embodying my invention 15 to walls or ceilings, it may be secured in place by any suitable means such as cleats, strips or nails but I prefer to secure the material to surfaces by a cementing agent such as a high melting point pitch or asphalt or other plastic or liquid 20 setting material. The cementing agent may be carried by the strips or panels themselves and applied to the reverse or unprinted side thereof so that it is only necessary for the user to moisten the material with water or a solvent or 25 heat the cement agent before applying the material to a surface. The troublesome selection and use of paste, cement and the like usually necessary with wall paper and floor coverings 30 may thus be avoided.

In order that my invention may be more clearly understood I have illustrated the same in the figures of the accompanying drawing as applied to strips of material adapted to be printed on a flat bed, block printing machine although it will 35 be apparent that my invention is not confined to its use with such material or to the use of such printing operations since any well known printing process using rolls or hand operations may be used.

In the drawing:

Fig. 1 is a perspective of a strip of material embodying my invention indicating the relation of said strip to other similar strips in a web 45 of material from which it may be formed.

Fig. 2 is a diagrammatic representation of one form of apparatus adapted for use in producing the material.

Fig. 3 is an enlarged sectional view of the material as applied to a surface.

Fig. 4 illustrates an alternative form of surface layer of the material and

Fig. 5 illustrates a rigid construction embodying my invention.

In that form of my invention chosen for purposes of illustration in Figs. 1 and 3 the material comprises a strip 2 of material such as waterproof asbestos or impregnated paper, pulp board, asphalt saturated felt or the like. The strips may be formed by severing a relatively long web 4 60 of the material transversely along line 5 or by severing the web or sheet at longer intervals when the article is produced from a narrow web. To one surface of the material a waterproof enamel or other suitable decorative substance of 65 a durable nature is applied as indicated generally at 6. The material is printed or otherwise formed to provide a border 8 on one end of the strip which as illustrated simulates a baseboard while the opposite end of the material is provided with a border 10 of the type designed to be 70 located adjacent the ceiling of a room. The body of the strip between the borders 8 and 10 is provided with a surface layer 12 in a design which simulates ordinary wall paper whereas the 75

portion 14 of the water resistant layer is formed to simulate wainscoting. If preferred the portion 12 having a wall paper design may extend all the way from the border 8 to the border 10 and in some instances even the border 10 may be omitted. It may also be desirable at times to provide the strip with a uniform design throughout, omitting both borders but ordinarily this type of design is not so desirable since many of the 10 advantages of the product are thereby sacrificed. It will be evident that the design may be varied as desired to form the material for use as a substitute for wall paper, wood panelling, wainscoting, tile or any other part or all of the 15 forms of wall coverings now in use.

In printing the material on a flat bed block printing machine of the type commonly employed in producing felt base rugs a web 4 of the material or successive preformed units forming the 20 base member are passed from a roll 16 or other feed device at the right hand end of the machine as shown in Fig. 2 and are moved over the bed 18 of the machine and beneath each of a number of printing blocks 20, 22, etc. represented diagrammatically in the drawing. Each of the 25 blocks will ordinarily extend the full width of the machine, as in standard practice, so as to print one of the colors of a complete design on a strip to be cut transversely from the web or on a unit 30 having passed over the bed 18. The web of material or the unit after being printed by the first block 20 is moved forward in a step by step movement so as to bring that strip or unit of the material into registration beneath a succeeding 35 printing block 22 while a succeeding section or unit is being printed by the first block. The first block 20 prints one portion or one color of the design whereas the second block 22 applies a different color or a different portion of the 40 design on the same section of material or unit in the interval between every alternate forward movement of the material. After being printed by the second block the material is moved on to bring each strip or section into position 45 beneath each of the other blocks on the machine until all of the colors or the whole design has been printed.

When the material is formed from a web having transversely printed designs, such as that 50 presented in Fig. 1, applied thereto and preferably with a complete design printed on each section thereof, the web is then passed on to a cutting device represented at 24 which severs the web transversely on the lines 5 between each section of the material or between each completed design. The material may be dried or cured before it is cut or the web may be cut in transverse strips as soon as completely printed. The 55 strips or units preferably have substantially the same dimensions as the blocks by which they are printed but they may be made of any desired length or width adapted for use in applying the same to a wall of a room.

Strips of material having a design such as 60 that of Fig. 1 may be trimmed at either end to shorten the same or may be severed along one or more of the lines 26, 28 and 30 to remove a portion of a section of the material if it is to be applied to a room with a very low ceiling. Thus material having the same design may be 65 applied to rooms varying greatly in height while preserving the benefit of a single unit embodying various elements of a wall covering.

In securing the material to the walls of a 70 building or to other surfaces as illustrated in Fig.

3 I prefer to use a cementing agent shown at 32 which may be carried by the material itself or applied directly to the surface of a wall 34. The strips are placed with their adjacent edges 36 abutting and are pressed onto the wall to insure firm and permanent application thereof to the surface. However, the strips may of course be secured in place by any other suitable means without departing from my invention.

By the use of material formed with designs 10 and borders in the manner described, the strip may be made of a standard size while at the same time it is applicable for use in rooms varying greatly in height. The material may be printed with a wood panelled effect to adapt it for use 15 in dining rooms, libraries and elsewhere where such constructions are desirable but have heretofore been very expensive. By the use of a different design material of the same type may be applied to bedrooms, nurseries, bathrooms, 20 kitchens or elsewhere where it is desired to provide a durable, washable wall surface which does not have to be frequently renewed and which retains its attractive appearance under severe usage.

As illustrated in Fig. 4 the borders, figures or elements of design may be raised as to 38, sunken as at 40, or produced by the application of separate members to the base member as at 42. The surface layer also may be given a raised or 30 embossed effect by a second printing operation, using printable material of a heavier or different character or by an embossing or other operation as desired.

In embodying my invention in a rigid construction in the manner shown in Fig. 5 the base material may consist of a preformed board such as cement-asbestos products or those products marketed under the trade names "Celotex", "Beaverboard", etc. Material formed as described above by which the design and effect are carried may be applied directly to a surface of the rigid base material 44. The latter form of product is adapted for use in forming a finished decorated wall, avoiding the use of lath and 45 plaster or for use in erecting light and inexpensive partitions or surfaces which have an attractive appearance but which may easily be put in place and removed. Ordinarily, however, I prefer to form the material as a flexible product of light 50 weight and simple construction with one or more of the strips in a piece.

While I have illustrated and described certain preferred forms of wall covering embodying my invention it will be evident that it is capable of 55 various modifications in form, structure and design to adapt it for use in any of a great variety of structures, rooms and buildings and for various purposes.

What I claim is:

1. A preformed wall covering of variable length adapted to be applied to the walls of rooms of different height comprising a unit of greater length than width embodying a base member and having water resistant decorative material 65 applied to adjacent areas of said base member in individually complete designs arranged in a predetermined relation lengthwise of the unit with the edges of the designs extending transversely of said unit, the decorative material applied to each of said areas simulating a conventional type of wall covering and the designs on adjacent areas simulating wall coverings of different types, said unit being severable along the edges of said areas to remove a part or all of 70 75

an area without impairing the design on the remainder of said areas whereby wall covering shorter in length than said unit but containing each of said designs may be produced from said unit.

5. 2. A preformed wall covering of variable length adapted to be applied to the walls of rooms of different height comprising a unit of greater length than width embodying a strip of asphalt 10 saturated felt having water resistant decorative material applied to adjacent areas and in individually complete designs arranged lengthwise of said strip in predetermined relation and with the edges of said areas extending in substantially straight lines transversely of said strip, 15 said decorative material being applied to adjacent areas of the base member in the form of different designs, the designs of said material on each of said areas simulating a conventional type of wall covering and the designs on adjacent areas simulating wall coverings of different types, said unit being severable along the edges of said areas to remove a part or all of an area without impairing the design on the remainder of said areas whereby wall covering shorter in length than said unit but containing each of said designs may be produced from said unit.
20. 3. A preformed wall covering of variable length adapted to be applied to the walls of rooms of different height comprising a unit of greater 25 length than width embodying a base member which areas are arranged longitudinally of said unit, the decorative material applied to an area adjacent one end of the unit being arranged to simulate woodwork and the decorative material applied to another area being arranged to simulate a different type of conventional wall covering material whereby wall covering shorter in length than said unit but containing each of said designs may be produced from said unit.

length than width said unit embodying a rigid base member having a layer of waterproof decorative material applied to a surface thereof, said material being applied to adjacent areas of said base member in the form of different individually 5 complete designs arranged in predetermined relation and each simulating a different type of conventional wall covering, said unit being severable along the edges of said areas to remove a part or all of an area without impairing the design on the remainder of said areas whereby wall covering shorter in length than said unit but containing each of said designs may be produced from said unit.

4. A preformed wall covering of variable length 15 adapted to be applied to the walls of rooms of different height comprising a unit of greater length than width embodying a base member and having water resistant decorative material applied to adjacent areas of said base member 20 which areas are arranged longitudinally of said unit, the decorative material applied to an area adjacent one end of the unit being arranged to simulate woodwork and the decorative material applied to another area being arranged to simulate a different type of conventional wall covering material whereby wall covering shorter in length than said unit but containing each of said designs may be produced from said unit.

JOHN TOMEK. 30
